UNITED STATES PATENT OFFICE

DOUGLAS W. BRASHEAR, OF RICHMOND, VIRGINIA

AUCTION WAREHOUSE

Application filed May 23, 1930. Serial No. 454,992.

My present invention relates to auction warehouses and more particularly to warehouses from which leaf tobacco is sold at auction.

According to the practice now universally employed in the selling of leaf tobacco, central warehouses are provided in the different tobacco growing sections of the country from which the tobacco is sold. The tobacco farmers bring their cured tobacco to these warehouses during the selling season. They first grade the tobacco according to quality in the customary way and when reaching the warehouse it is placed into relatively large and shallow tray-like baskets, each holding anywhere from fifteen to several hundred pounds. Each basket carries a removable tag or card, usually in triplicate, bearing the basket number, the name of the grower and the quantity of tobacco in pounds contained in each basket. Prior to the auction period these baskets of tobacco belonging to the different growers are arranged in spaced rows upon the floor of the warehouse, the spaces between each two rows of baskets being sufficiently wide to provide an aisle.

The warehouseman, auctioneer, his clerk (called a "tag marker") and the various buyers then walk up and down the several aisles, the sales taking place while the group is walking. As each basket of tobacco is sold the clerk marks on the tag or card the price per pound, name of the buyer and the grade of tobacco. The tag is then replaced on the basket. Other clerks, following the group, enter in books and on bills of sale the information shown on the tags. This procedure continues until all the tobacco in the baskets on the floor has been sold, and the baskets with the tobacco therein are then collected by the various buyers and the tobacco is placed in trucks and carted to the private warehouses of the buyers, after which a fresh supply of baskets with tobacco is arranged on the warehouse floor as before and the procedure is repeated from day to day until the year's crop has been disposed of.

Before the baskets of tobacco are placed on trucks to be removed from the warehouses,

an employee of the buyer removes the triplicate copy of the tag or card from each basket of tobacco and signs the buyer's name thereon as a record showing the buyer to whom the tobacco is delivered. This signed triplicate tag or card is retained by the sales warehouse. The original and duplicate tags or cards remain on each basket of tobacco, giving the buyer a record when it is received at his private warehouse.

The selling and handling method described, if it is to be profitable to the warehouse owner, requires a warehouse having considerable floor space area and a relatively large number of men in order to handle any appreciable quantity of tobacco during a given period, say an ordinary working day between the hours of 9 A. M. and 5 P. M. The business of selling at auction can hardly be made to pay unless a relatively large quantity of tobacco can be sold each day because it is sold on a commission basis.

By the present method of selling it will be clear that the quantity of tobacco sold during each session or day will depend very largely upon the floor space of the warehouse, and in addition to this limitation in the sales possibilities per session or day, the prevailing method requires the employment of a relatively large number of men to handle the tobacco, and besides the procedure is laborious and tiresome to the warehouseman, his auctioneer, his clerks and the buyers who must walk up and down the aisles between the tobacco baskets until all the baskets of tobacco have been sold.

The objects of the present invention are to facilitate the handling and sale of commodities, such as tobacco, in the auction warehouse; to lessen the floor space required by being able to stack the tobacco, by placing several baskets of tobacco on top of each other; to expedite and lessen the cost of making sales, thus allowing for the sale of a greater quantity in a given time and at less expense, because fewer laborers are required; to render the selling operation less tedious and tiresome to the warehouseman, his auctioneer, his clerks and the purchasers, and to otherwise aid the whole operation.

To this end my invention comprises an auction warehouse with ample storage space for the commodity to be sold, transporting means therein so constructed and arranged that the commodity to be sold, such as tobacco, will be transported from a "receiving station" thru or past a "selling station", constructed in a manner and of materials to give a maximum of daylight, where the warehouseman, his auctioneer, clerks and the purchasers may be comfortably located, to a plurality of "delivery stations" where the sold commodity may be easily removed from the said means and quickly loaded onto motor trucks or other conveyances to be hauled away.

The improved apparatus, while particularly designed for use in tobacco auction warehouses, is equally applicable in other auction rooms, wherein a large number of articles are to be sold in succession. The invention includes as its essential features, a receiving station, where ample storage facilities are provided for the articles, as, for instance, the tobacco to be auctioned; a plurality of delivery stations, and a selling station, together with some means enabling the articles to be transported from the receiving station to the delivery station, through or past the selling station.

Any preferred type of transporting means may be used. The merchandise is transported in lots, as, for instance, tobacco in baskets, past the selling station, in condition such that it may be easily inspected by the prospective buyers, to enable them to determine whether or not to bid upon a lot or lots. The delivery stations are preferably provided with some type of distributing means, in order to enable the lots to be quickly set aside or removed, to prevent interference with succeeding lots, as they arrive.

In the drawings forming a part hereof:—

Fig. 1 is a plan view of a warehouse floor, with the walls in section constructed in accordance with the invention.

Fig. 2 is a section on the line 2—2 of Fig. 1.

Fig. 3 is a sectional view at right angles to Fig. 2.

Fig. 4 is an enlarged detail in side view of a part of the conveyor.

Fig. 5 is an enlarged detail in transverse section at the delivery end of the conveyor.

Fig. 6 is a detail in plan of a part of one of the chains of the conveyor.

Fig. 7 is a plan view of another arrangement.

Fig. 8 is a side elevation.

Fig. 9 is an enlarged detail in section on the line 9—9 of Fig. 8.

Fig. 10 is an enlarged detail in side view at the delivery end.

Fig. 11 is a similar view at the receiving end.

In the present case two preferred embodiments of the invention are shown and de-

scribed, the principal difference between them being the arrangement at the delivery end for distributing the lots or containers.

In the embodiment of the invention shown in Figs. 1 to 6 inclusive, the warehouse, the side and end walls of which are indicated at 1 and 2, respectively, have appropriate door openings 3, and a driveway 4 is provided at each side of the building just inside the adjacent side wall, each driveway opening at each end of the warehouse. Inside driveways are, however, optional, as outside driveways may be employed without departing from the spirit of the invention.

In the usual arrangement, as previously pointed out, the tobacco in suitable containers, such as baskets, indicated at 6, is arranged upon the floor of the warehouse, being delivered from vehicles on the driveway, and these baskets are stored on the floor until the time of sale, when the auctioneer, and interested parties, travel about the floor space, dealing with the individual baskets.

In the present instance, a "selling station" which may be in the form of a room or compartment 7, is provided within the warehouse, preferably somewhat near the center, and this compartment has windows 8, as shown, and a door opening 9, enabling access thereto. While a separate room or compartment has its advantages, it is not absolutely essential. A transporting means, indicated generally at A and of any desired construction, is arranged to convey the tobacco from the receiving end of the warehouse, at the right of Fig. 1 to the delivery end at the left of Fig. 1, and the conveyor passes through the compartment 7, as shown, openings 10 being provided for enabling the passage.

Seats 11 are provided within the compartment at the opposite sides of the conveyor, for the buyers, and other interested parties, and the travel of the conveyor through the compartment is controlled from a control station indicated generally at 12, the arrangement being such that the speed of the conveyor may be controlled, and it may be stopped and started at will, if desired, for any purpose. At the delivery end of the conveyor the baskets of tobacco are removed therefrom, and are preferably disposed laterally with respect to the conveyor. There are usually some "rejects", that is, some baskets of tobacco, which do not find a sale, and means is provided preferably in line with the conveyor's movement, for receiving the rejects at the delivery end.

In the present construction, the transporting means is in the form of a conveyor composed of two endless chains, similarly arranged, side by side, spaced apart laterally from each other, and connected in a manner to be described. Each chain is composed of pairs 16 and 17 of links, the pairs 16 alternating with the pairs 17. The ends of each

pair 16 are pivotally connected to the adjacent ends of the adjacent pairs 17, as shown, the connection being indicated at 18, and the inner members of the pairs 17 have inwardly extending lugs 19. The lugs 19 of the registering links of the two chains are connected by cross plates 20.

The chains are supported at their ends by suitable sprocket wheels 13, mounted in supporting brackets 14. At the receiving end, the sprockets 13 are preferably arranged below the level of the floor 15, so that the upper run of the conveyor is substantially flush with the floor level. As the conveyor 15 approaches the compartment 7, the level of the upper run is preferably raised to approximately ten inches, and held at this height until it passes beyond the selling station or compartment, as shown in Fig. 2.

Thus within the compartment it is at a suitable height to enable the tobacco in the baskets supported thereon to be readily inspected by buyers in the compartment.

Beyond the compartment 7 the level of the upper run of the conveyor is again raised to approximately thirty inches, and this level is maintained to the delivery end. In practice, the lower run of the conveyor is substantially parallel with the upper run, and each chain is provided with rollers 21 between the members of the pairs of links at the pivotal connections, and the rollers run upon angle plates 23, supported by a suitable framework indicated generally at 24, and of any desired character. The angle plates 23 extend the full length of the upper and the lower runs of the conveyor, so that each chain has guided movement throughout its extent, both as to the upper and to the lower run.

The conveyor may be driven by any suitable motor, as for instance, the electric motor 25, which is connected to the shaft 26, supporting the sprocket wheels at the delivery end of the conveyor by any suitable connection. The baskets of tobacco, or other commodity to be sold, are placed on the upper run of the conveyor by attendants, and are carried to and through the "selling station" 50 or compartment 7, which contains the auctioneer, his clerks, and the buyers. Each lot that is sold is provided with a tag or ticket indicating the buyer, and the speed with which the containers move through the compartment may be nicely regulated by the auctioneer, or some other person in the compartment.

The tobacco sold is removed from the conveyor at "delivery stations" located near the delivery end, being pushed off the conveyor onto the platforms indicated generally at 27, each of which may be provided with rollers 28, over which the tobacco containers may move easily, as shown in Figs. 1 and 5. The platforms extend laterally from both sides

of the conveyor, and they are preferably arranged, as shown in Fig. 1, in sets of two, and a pair of rails 30 may extend from each set of two platforms to the driveway at the adjacent side of the building.

Trucks 31 are arranged to roll upon the rails, and one or more of the platforms may be assigned to each buyer, or at least to each buyer of large quantities of tobacco. As the containers of tobacco arrive at the appropriate platform, they are removed from the conveyor as indicated by the tickets connected therewith. If a truck is at that moment in position to receive a load, the containers are pushed out along the platforms, moving on the rollers 28, and are loaded onto the trucks. If no truck is available, they may be stored temporarily on the platform.

In every sale there are some lots which will not be purchased, and which are disposed of by removing them from the conveyor A to a supplemental conveyor, arranged in alignment with the conveyor A, at the delivery end thereof, this conveyor being indicated at B, and it may be a conveyor, or merely a platform, like those shown at 27. As the rejected lots or parcels collect on the element B, they may be removed to the floor of the warehouse. It will be noticed, referring to Fig. 5, that each of the platforms 27 is supported by a suitable framework 32.

In operation, the tobacco as it is delivered to the warehouse, is stored on the floor, until the time to sell. At this time, the baskets of tobacco are placed one by one on the transporting means, and the buyers, and the auctioneer and his attendants being in the compartment 7, the conveyor begins to move the baskets through the compartment.

The speed may be nicely controlled, to give ample time for inspection and sale, and as each load is bid off, a ticket indicating the ownership is attached to the basket. At the delivery stations indicated by the unloading platforms, there are attendants, who remove the ticketed baskets at the appropriate platforms, from whence they are removed by the trucks 31, and eventually delivered to other means of conveyance on the driveway.

In Figs. 7 to 11, another embodiment of the invention is shown. By this arrangement, the buyer's compartment 33, corresponding to compartment 7, is arranged within the warehouse in the same manner as the compartment 7, and is similarly provided with seats, door and window openings, and a control for the conveyor to be described. The transporting means runs through the compartment from end to end thereof, and is composed of endless chains 34, supported at suitable intervals by sprocket wheels 35, mounted on shafts 36, journaled in a framework 37.

The chains are similarly arranged, in parallel laterally-spaced relation, and the shaft 36 at the delivery end of the conveyor is con-

nected by suitable belts or gearing to a motor 38. The shaft 36 at the inlet end is adjustably mounted in its bearings, in the manner shown in Fig. 11. The shaft is journaled in 5 blocks 39, which are slidable in guides 39', and screws 40 are threaded through the frame and are rotatably connected with the blocks. It will be apparent that by turning the 10 screws, the shaft may be moved toward or from the shaft at the delivery end, whereby to tension the chains. The chains are connected at suitable intervals by cross rods 41, and the upper and lower runs of the chains move along angle guides 42 on the frame 37. 15 The baskets 43 of tobacco are seated on the chains, in front of the rods 41, as indicated in Fig. 9, so that the rods assist in moving the baskets.

Referring to Fig. 8, it will be noticed that 20 the upper run of the conveyor is substantially level from its inlet end to a point beyond the compartment 33. The delivery end of the conveyor is then inclined upwardly, as shown in Figs. 8 and 10, the inclination being obtained by inclining that part of the 25 frame 37. A turntable 44 is arranged at the delivery end of the conveyor, in a position such that the baskets may pass from the upper end of the conveyor onto the table, and 30 the table may or may not be rotatable on a support 45 on the floor of the warehouse. A plurality of delivery stations in the form of platforms are arranged about the turntable, the platforms diverging from the table as 35 shown, at various angles. Each platform may consist of a suitable framework 46, supporting the platform bars 47, and rollers 48 are journaled on the bars 47, the said bars inclining downwardly as shown.

40 Referring to Fig. 10, it will be seen that tension rollers 49 are provided for the lower runs of the chains at the motor or delivery end, these rollers being supported from the frame. The connection between the motor 45 38 and the shaft 36 at this end is by means of a chain and sprocket connection 50. In the present instance, the compartment roof is railed in, as shown at 51, and a stairway 52 is provided for enabling access to the roof. In 50 case of many buyers, some may be accommodated on the roof, a longitudinal opening being provided above the conveyor for permitting inspection of the tobacco carried thereby.

55 In operation, it being understood that the embodiment just described is arranged in the warehouse, the tobacco from the growers, is deposited as above described, and during the auctioning of the tobacco, the baskets are 60 placed on the conveyor, and are moved through the buyers' compartment. As each lot is sold, it is tagged, as above described, and when the baskets pass onto the turntable, they are removed to the several platforms, in 65 accordance with the name of the buyer, a

platform being assigned to each buyer, or each buyer of large quantities. The operation is practically the same as in the embodiment shown in Fig. 1.

While I have shown and described two 70 embodiments of the invention, it will be readily apparent that other arrangements may be employed without departing from the broad spirit thereof, as herein described, and I do not wish to be understood as limiting myself to either of the constructions shown and described and this has special reference to the two conveyor constructions illustrated, as any suitable transporting means may be employed for the purpose. 75

While the transportation means shown in Fig. 1 is elevated above the floor line, and arranged to move at different levels, it is apparent that this is optional. It may be at floor level, and on the same level throughout 80 if desired. It will be understood that after the tobacco is sold in the improved warehouse, the same procedure is followed in marking the tags which are carried by the baskets, and in entering the information on 85 the tags in the books and bills of sale. 90

What is claimed is:—

1. An auction warehouse comprising a main floor having a receiving station at one end with provision for storing a quantity of the commodity to be sold, a selling station intermediate the ends of the warehouse, a plurality of delivery stations at the other end of the warehouse, and an endless conveyor leading from the receiving station 95 through the selling station and terminating at the delivery stations, the upper run of said conveyor being at substantially floor level at the receiving station. 100

2. An auction warehouse comprising a main floor having a receiving station at one end with provision for storing a large quantity of the commodity to be sold, a selling station intermediate the ends of the warehouse, and a plurality of delivery stations 105 near the other end of the warehouse, and an endless conveyor leading from the receiving station through the selling station and terminating at the delivery stations, the upper run of said conveyor being at substantially floor level at the receiving station, and at a higher level at the delivery stations. 110

3. An auction warehouse for the sale of tobacco, comprising an enclosure having a main floor providing a receiving station at one end of the warehouse having sufficient floor area to store a large number of open top receptacles containing the tobacco to be sold, a selling station arranged substantially centrally of the main floor and provided with accommodations for an auctioneer, his clerk and buyers, travelling transporting means for conveying a train of the tobacco containers successively from the receiving station 120 through the selling station to near the other 125 130

end of said warehouse floor, a plurality of delivery exits at said last-named end of the warehouse, and a plurality of wheeled transporting means for transporting the receptacles of sold tobacco from the conveying means to the separate delivery exits.

4. An auction warehouse for the sale of tobacco, comprising an enclosure having a main floor providing a receiving station at one end of the warehouse having sufficient floor area to store a large number of open top receptacles containing the tobacco to be sold, an enclosed selling station arranged substantially centrally of the main floor having openings at its opposite ends and provided with accommodations for an auctioneer, his clerk and buyers, endless conveying means for transporting a train of the tobacco containers successively from the receiving station through said opening in the selling station to near the other end of said warehouse floor, a plurality of separate delivery exits at said last-named end of the warehouse, and a plurality of wheeled transporting means for transporting the receptacles of sold tobacco from the conveying means to the separate delivery exits, one leading to each exit.

5. An auction warehouse for the sale of tobacco, comprising an enclosure having a main floor providing a receiving station at one end of the warehouse having sufficient floor area to store a large number of open top receptacles containing the tobacco to be sold, a selling station arranged substantially centrally of the main floor and provided with accommodations for an auctioneer, his clerk and buyers, endless conveying means movable over the warehouse floor for transporting a plurality of the tobacco containers successively from the receiving station through the selling station to near the other end of said warehouse floor, a separate delivery exit at opposite sides of said last-named end of the warehouse, and a plurality of means at opposite sides of the conveying means for transporting the receptacles of sold tobacco from the conveying means to the separate delivery exits, one leading to each exit.

6. An auction warehouse for the sale of tobacco, comprising an enclosure having a main floor providing a receiving station at one end of the warehouse having sufficient floor area to store a large number of open top receptacles containing the tobacco to be sold, a selling station arranged substantially centrally of the main floor and provided with accommodation for an auctioneer, his clerk and buyers, endless conveying means for transporting the tobacco containers successively from the receiving station through the selling station to near the other end of said warehouse floor, delivery exits at said last-named end of the warehouse, and a plurality of means for transporting the receptacles of sold tobacco from the conveying means to

said delivery exits, a portion of said endless conveying means at the receiving end of the warehouse being at substantially floor level.

7. An auction warehouse for the sale of tobacco, comprising an enclosure having a main floor providing a receiving station at one end of the warehouse having sufficient floor area to store a large number of open top receptacles containing the tobacco to be sold, a selling station arranged substantially centrally of the main floor and provided with accommodations for an auctioneer, his clerk and buyers, an endless conveyor movable over the floor of the warehouse for transporting the tobacco containers successively from the receiving station through the selling station to near the other end of said warehouse floor, a plurality of delivery exits at said last-named end of the warehouse, tracks leading from the conveyor to each exit, wheeled trucks movable over said tracks for transporting the receptacles of sold tobacco from the conveying means to the separate delivery exits, and a manually operable controller at the selling station for regulating the movement of the conveyor.

8. An auction warehouse for the sale of tobacco, comprising an enclosure having a main floor providing a receiving station at one end of the warehouse having sufficient floor area to store a large number of open top receptacles containing the tobacco to be sold, a selling station arranged substantially centrally of the main floor and provided with accommodations for an auctioneer, his clerk and buyers, an endless conveyor movable over the floor of the warehouse for transporting the tobacco containers successively from the receiving station through the selling station to near the other end of said warehouse floor, a plurality of delivery exits at said last-named end of the warehouse, tracks leading from the conveyor to each exit, wheeled trucks movable on said tracks for transporting the receptacles of sold tobacco from the conveying means to the separate delivery exits, and receiving platforms adjacent the delivery end of the said endless conveyor onto which the receptacles of tobacco may be loaded for delivery on to said trucks.

9. An auction warehouse for the sale of tobacco, comprising an enclosure having a main floor providing a receiving station at one end of the warehouse having sufficient floor space to store a large number of open top receptacles containing the tobacco to be sold, a selling station arranged substantially centrally of the main floor and provided with accommodations for an auctioneer and buyers, an endless conveyor for transporting the tobacco containers successively from the receiving station through the selling station to near the other end of said ware-

- house floor, a portion of said endless conveyor being at substantially floor level at the receiving station, and at a higher level at a point beyond the selling station, receiving 5 platforms adjacent the conveyor at the receiving station, and a plurality of means for transporting the receptacles of sold tobacco from the said platforms to the said delivery exits. 70
10. An auction warehouse for the sale of tobacco, comprising an enclosure having a main floor providing a receiving station at one end of the warehouse having sufficient floor area to store a large number of open 75
- 15 top receptacles containing the tobacco to be sold, a selling station arranged substantially centrally of the main floor and provided with accommodations for an auctioneer and the buyers, an endless conveyor for transporting 80
- 20 a train of tobacco containers successively from the receiving station through the selling station to near the other end of said warehouse floor, a plurality of separate delivery exits at the opposite sides of 85
- 25 the last-named end of the warehouse, separate tracks leading from the conveyor to each exit, and a plurality of wheeled trucks movable on said tracks for transporting the receptacles of sold tobacco from the conveyor 90
- 30 ing means to the respective delivery exits. 95
11. An auction warehouse comprising a main floor having a receiving station at one end with sufficient floor area to store a large number of stacks of portable receptacles containing tobacco to be sold, a plurality of unobstructed delivery stations at the other end of the warehouse at which the sold tobacco may be delivered to be loaded into vehicles to be carted away, a selling station located 100
- 35 intermediate the ends of the warehouse floor, and of sufficient size to provide seating accommodations for an auctioneer, his clerk, and a number of buyers, travelling transporting means movable over the floor of the 105
- 40 warehouse and leading from the receiving station, through the selling station, to a position substantially opposite the said delivery stations to transport a succession of tobacco receptacles through said selling station, and a plurality of wheeled trucks each movable along a separate path from adjacent that portion of the transporting means located beyond the selling station to one of said delivery stations, whereby the separate 110
- 45 receptacles containing the sold tobacco may be readily transferred from the transporting means onto the trucks to be delivered at the said delivery stations. 115
- 50 12. An auction warehouse comprising a main floor having a receiving station at one end with sufficient floor area to store a large number of stacks of portable receptacles containing tobacco to be sold, a plurality of unobstructed delivery stations leading from 120
- 55 the other end of the warehouse at which the 125
